US00D908101S

(12) **United States Design Patent** (10) **Patent No.:** **US D908,101 S**
Tarapoom et al. (45) **Date of Patent:** **** Jan. 19, 2021**

(54) **MICROCHANNEL HEAT EXCHANGER**

(71) Applicants: **PTT Global Chemical Public Company Limited**, Bangkok (TH); **PTT Public Company Limited**, Bangkok (TH)

(72) Inventors: **Nattapong Tarapoom**, Bangkok (TH); **Kawisra Sompech**, Bangkok (TH); **Nichaporn Sirimungkalakul**, Bangkok (TH)

(73) Assignee: **PTT Global Chemical Public Company Limited**, Bangkok (TH)

(**) Term: **15 Years**

(21) Appl. No.: **29/692,339**

(22) Filed: **May 24, 2019**

(30) **Foreign Application Priority Data**

Nov. 26, 2018 (TH) 1802005133

(51) **LOC (13) Cl.** **13-03**

(52) **U.S. Cl.**

USPC **D13/179**

(58) **Field of Classification Search**

USPC D13/179, 182, 199; D23/261, 354, 365, D23/388, 393, 397; D25/142; D5/1, 2, D5/3, 56

CPC F28D 9/0037; F28D 9/0043; F28D 9/0062; F28F 3/025; F28F 3/046

Primary Examiner — Selina Sikder

(74) *Attorney, Agent, or Firm* — Baker & McKenzie LLP

(57) **CLAIM**

The ornamental design for a microchannel heat exchanger, as shown and described.

DESCRIPTION

FIG. 1 is a perspective view of my new design;
 FIG. 2 is a top plan view of my new design;
 FIG. 3 is a bottom plan view of my new design;
 FIG. 4 is a right elevation view of my new design;
 FIG. 5 is a left elevation view of my new design;
 FIG. 6 is a front elevation view of my new design; and,
 FIG. 7 is a rear elevation view of my new design.

1 Claim, 7 Drawing Sheets
